UNITED STATES PATENT OFFICE

110,848

DESIGN FOR A COMBINED COAT AND CAPE

Roy W. Hill, Chicago, Ill.

Application January 28, 1938, Serial No. 74,683

Term of patent 14 years

To all whom it may concern:

Be it known that I, Roy W. Hill, a citizen of the United States, residing at Chicago, in the county of Cook and State of Illinois, have invented a new, original, and ornamental Design for a Combined Coat and Cape, of which the following is a specification, reference being had to the accompanying drawing, forming a part thereof.

Fig. 1 is a front elevation of a combined coat and cape embodying my design;

Fig. 2 is a rear elevation of the same; and

Fig. 3 is a front elevation similar to Fig. 1, showing the same partly opened.

I claim:

The ornamental design for a combined coat and cape, as shown.

ROY W. HILL.
